UNITED STATES PATENT OFFICE.

ROBERT T. WATT, OF LAUREL SPRINGS, NEW JERSEY.

AUTOMATIC TELEPHONE-SWITCH.

SPECIFICATION forming part of Letters Patent No. 651,540, dated June 12, 1900.

Application filed April 12, 1900. Serial No. 12,511. (No model.)

To all whom it may concern:

Be it known that I, ROBERT T. WATT, a citizen of the United States, residing at Laurel Springs, in the county of Camden and State 5 of New Jersey, have invented new and useful Improvements in Automatic Telephone-Switches, of which the following is a specification.

My invention relates to intercommunicating automatic telephone-switches for use in large factories, department stores, and similar buildings where it is desirable to have telephonic communication with the various departments or rooms; and the object of my 15 improvement is to provide mechanism whereby any particular telephone in the system may be quickly and easily put in communication with any other telephone in the same system without ringing up all the other instruments 20 on the line and without having a special attendant to manipulate a switchboard.

In order that my automatic switching device may be put in operation, it is necessary that the telephone at each station be placed 25 on a separate line and each line pass through all of the other stations instead of to a centrally-located switchboard. The particular arrangement of the wires for telephones of this class being well known, I have not shown 30 these connecting-wires.

In the accompanying drawings, Figure 1 is a front elevation of a telephone provided with my automatic switch. Fig. 2 is a rear elevation of the telephone, showing the switching mechanism. Fig. 3 is a sectional view through the switching device, as on line $\alpha\alpha$ of Fig. 1. Fig. 4 is a sectional view on line $\gamma\gamma$ of Fig. 2.

A represents the wooden case inclosing the 40 switch mechanism; B, the transmitter; C, the receiver, having the usual connections; D, the hook upon which the receiver is suspended. This hook is of the usual and well-known form, being provided with contact-plates and 45 pivoted at a.

E is a call-bell; E', the push-button connected with all of the call-bells in the system.

F is a metal plate fastened on the front of the case A and having thereon figures that 50 indicate the floors or rooms to be communicated with.

a' is a finger or pointer to indicate the room with which telephonic connection is being had.

b b b are small contact-plates fastened on

the inside of the case, being one for each floor 55 or room to be communicated with.

b' is a long contact-plate connected by wire to the receiver C.

c is a movable contact-plate adapted to slide over and form electrical connections between the long plate b' and the several short plates b b.

a² is a projecting post or stud formed on the end of the part that carries the sliding contact-plate c. This post slides along the 65 edge of the lever A' and is adapted to enter the notches therein. The sliding contact-plate c is fastened or connected to a head-piece a³, that slides over and upon the rod b², secured in the case A.

b³ is a spiral spring fitting over the rod b² and under the movable headpiece a³, to which it is attached in the manner shown in Fig. 2.

A' is a notched lever, one end of which is pivoted at c' to the inside of the case A, the opposite end having attached thereto the spiral spring c², fastened to the side of the case A. This lever A' is provided with a notch for each room or floor above No. 1.

c³ is a post or projection secured on the face 80 of the notched lever A'.

c⁴ is a strap or loop fastened on the notched lever A' near the post c³.

B' is an arm or lever the free end of which passes through the loop c⁴ and the opposite 85 end pivoted to the bell-crank lever B², pivoted at d to the inside of the case A. One end of the bell-crank lever B² is bent outwardly at right angles to the main portion and is connected with the inner end of the 90 receiver-hook D by the link d', so that the lever B² is operated by the movement of the receiver-hook up or down as the receiver is placed upon or taken off of the hook.

d² is a slanting projection or hump formed 95 on the lever B' at or near the middle thereof.

d³ is a projecting post secured upon the inside of the case A in such a position that the surface of the inclined extension or hump d² will impinge against it as this lever is moved 100 back or forward.

d⁴ is a spiral spring one end of which is attached to the lever B' and the opposite end secured to the side of the case A. The forward end of the lever B' is provided with a 105 hook d⁵, that operates upon the post c³ on the notched lever A'.

The various parts of the switching mech-

anism are insulated wherever necessary, said insulations being indicated by the solid black portions shown in the drawings.

The several parts of my device being constructed and arranged as shown, with the receiver C hanging upon the hook D, the operation is as follows: The finger or pointer a' is pulled down until it points to the number of the room or floor with which the operator desires to communicate. This movement of the finger a' carries the post a^2 into the corresponding notch on the lever A' and brings the operator in electrical connection with the room indicated by the pointer a' . The signal is then given by pushing the button E', and thus ringing the call-bell in the room indicated by the pointer. After ringing the call-bell the receiver C is lifted from the hook D, and the conversation can be carried on as desired. When the receiver is taken up and the hook relieved of the weight, the spring d^6 , connected therewith, will force the hook upwardly, carrying with it the attached end of the bell-crank lever B^2 . This movement of the lever B^2 will project the arm or lever B' forward in such a position that the hook portion d^5 will fit around the post c^3 on the notched lever A' , being held in that position by the spring d^4 . When the conversation is finished, the receiver is hung upon the hook D, which is depressed by the weight of said receiver and carries down with it the attached end of the bell-crank lever B^2 , pulling back the arm B' and the notched lever A' , thus releasing the post c^3 and allowing the movable contact-plate c to be forced home and into the position shown in Fig. 2 by means of the spiral spring b^3 , acting on the headpiece a^3 . As the lever B' is pulled backwardly, the hump or inclined portion d^2 , impinging against the post d^3 , forces the lever B' down, thus releasing the hook d^5 from the post c^3 on the face of the notched lever A' , bringing the parts in the position shown in Fig. 2 and ready for another call when desired. Instead of using the spiral spring b^3 , sliding on the rod b^2 , for bringing the movable contact-plate c into position any other convenient device may be used for that purpose.

If desired, the lever B' may be permanently pivoted or fastened to post c^3 on the notched lever A' , and the post d^3 , hump d^2 , and spiral spring d^4 omitted, in which case to operate the switch properly it will be necessary to lift the receiver C from the hook D before setting the index-finger to the room-number.

Having thus described my invention, what I claim as new, and desire to secure by United States Letters Patent, is—

1. In a telephone switching device, the combination of the bell-crank lever B^2 , having one end connected to the receiver-hook, the arm or lever B' , attached to the end of the crank-lever B^2 , and having on its forward

end a hook portion, the suspended notched lever A' , having thereon a projection or post adapted to engage with the hook on the end of the lever B' , the movable headpiece a^3 , adapted to slide up and down and having thereon a post or extension adapted to fit into the notches in the lever A' , and connected with a movable contact-plate that forms an electrical connection between the small contact-plates b and long contact-plate b' , substantially as shown and for the purpose described.

2. In a telephone switching device, the combination of the bell-crank lever B^2 , having one end connected to the receiver-hook D, the lever B' , having thereon the hook portion d^5 , and the hump d^2 , impinging against the post d^3 , the suspended notched lever A' , having thereon the post c^3 , the series of small contact-plates b , and the long contact-plate b' , the movable headpiece a^3 , sliding over the rod b^2 , and connected with the contact-plate c , and having thereon an extension or post that fits into the notches on the lever A' , the spring b^3 , fitting over the rod b^2 , and the finger or pointer a' , connected with the headpiece and sliding over an index-plate, all arranged, substantially as shown and for the purpose described.

3. In a telephone switching device, the combination of the bell-crank lever B^2 , having one end connected to the receiver-hook, the arm or lever B' , one end of which is attached to the end of the crank-lever B^2 , and the opposite end attached to the suspended notched lever a' , a movable headpiece adapted to slide up and down and having thereon an extension adapted to fit into the notches in the lever A' , and connected with a movable contact-plate that forms an electrical connection between the small contact-plates b , and the long contact-plate b' , substantially as shown and for the purpose described.

4. In a telephone-switch, the combination of the pivoted bell-crank lever B^2 , one end of which is attached to the receiving-hook, the lever B' , jointedly connected at one end to the lever B^2 , the opposite end being connected to the suspended notched lever A' , the series of small contact-plates b , and the long contact-plate b' , the movable headpiece a^3 , carrying the contact-plate c , and having an extension that fits into the notches on the lever A' , the index-finger a' , connected with the movable headpiece, and the face-plate F, fastened on the front of the telephone-box and having thereon figures or letters that indicate the room to be communicated with, substantially as shown and for the purpose described.

In testimony whereof I affix my signature in presence of two witnesses.

ROBERT T. WATT.
